Charles H. Tooker

Spotters Patent April 8. 1834.

Printing Press

The schedule referred to in these Spotters Patent and making part of the same containing a description in the words of the said Charles H. Tooker himself of his improvement in the machine for Printing

To all whom it may concern, be it known that I Charles H. Tooker of New York in the County of Essex and State of New York have invented a new and useful machine for printing and I do hereby declare that the following is a full and exact description thereof references being had to the drawings which accompany and make a part of this specification. Fig 1. shows a perspective view of the whole machine and Fig 2. a vertical section taken longitudinally. In both these figures the parts which correspond are marked with the same letters of reference, as this machine is intended to be made both for large and small work. I do not deem it necessary to give the dimensions of the respective parts as a competent machinist will readily proportion these to suit the required purpose from the printing of single cards, to that of the large volumes of book work. The frame A A may be made in different forms, that represented in the drawing however I esteem convenient. The semicircular piece B with a corresponding piece on the opposite side supports the shaft C which passes through and revolves within the inking cylinder D and has a fly wheel on its opposite end to regulate the motion. When the press is at work this cylinder is stationary, its use being to sustain the force and to distribute the ink regularly upon the inking roller E. E. The form is placed vertically and is figure by means of wedges or otherwise in a frame, seen in section at B. The two ends of this frame are attached to sliding pieces at each end of the cylinder D. One of which is shown at Fig. figure 2. These sliding pieces serve as guides to the form, being retained in their places by proper guides. The shaft C has next to it a crank H, close to the head of the cylinder D which by means of two connecting rods I, jointed to the piece L, carry the sliding piece and the form A forward and forward. K. is a section of the platen which is adjustable, but may be set so as to regulate the pressure by means of the screw

R. H.

As working through a part of the frame. At the inking rollers E, E, are carried around the cylinder D by means of arms, one of which is shown at A, fastened at one end to the shaft C, and at the other to the frames which support the inking rollers. The guides of these rollers, consist in plots on the frame, being borne down by means of spiral or other springs, so as to keep them in contact with the cylinder D, and to force them down upon the type as they pass over the form. Although the large surface of the cylinder D, over which the inking rollers pass, will in general suffice to distribute the ink equally upon them, it is not sometimes to give to one or more of them with one a lateral motion which may be effected in various ways. The ink is to be contained in a reservoir A formed in the cylinder D, and reaching from one end of it to the other. Within this reservoir there is a supply roller P, one part of the periphery of which projects out above the surface of the cylinder D. The pinion D, is upon one of the guides and at the inking rollers actuates the teeth T, on the under edge of their frame giving to the roller a partial revolution, a catch which unlocks the pinion being lifted by a pin on the arm H. At the moment the teeth are to engage with the pinions this catch is thrown separately at figure F. Conveniences similar to those now in use may be employed to regulate the portion of ink which shall be brought round by this roller; this however may be in a great measure effected by the distance of its modulation, causing the inking rollers pass over it. The catches J, J, catch upon pins I, I, and hold the cylinder D in its place. These cause alternately when the frame of the inking rollers comes in contact with them, and thus allow it to pass. When the form is to be examined or covered both these catches are to be raised and the cylinder D will then turn on its shaft so as to allow the form to be brought into a horizontal position. In case of the machine to print with one or separate sheets in the ordinary way or to use a continuous sheet of any length that can be conveniently wound upon a roller. The mode of feeding, or laying on the sheet, must of course be adapted to these different purposes. A continuous sheet may be wound upon a roller placed immediately above the form and be conducted down between the feeding rollers R, R, or sheet may be fed from a board or sheet R, as it comes over in cylinder passes over an angle upon D, and between rollers R, R. The

tools are kept in their places against the sides upon by cords or strings in a manner well known in other prints. Fig. 3. shows the manner in which the motion is communicated from the shaft C. to the feeding rollers used to feed the paper. T. is a segment wheel on the shaft, the teeth on which take into the wheel a, having on it a groove which to receive a band. This band may pass round a wheel, with graduation grooves on the roller b, which is the same as D, in figs 1&2. The roller C, round which it is also thrown as passing carries the end of a iron X. d is a pulley for tightening the band, whilst the blank part of the segment wheel b, is passing round the feeding rollers, and the paper, and holding cords remain at rest, and the impression is then given by the advancing of the form against the platters, this occurring when the cranks on the shaft C, are turned the form. The ink will be passed over the form, when the cranks are in the reverse position, the pieces of the type then most nearly coinciding with the surface of the cylinder C. When I print upon a continuous sheet, I intend to divide the same as it is delivered from the form by means of a knife or of perforating points which may be arranged in various ways to operate at the right time. This however being a thing of arrangement only and not affecting the general principles upon which the machine operates, I do not deem it necessary to designate any particular mode of effecting this object. It will readily be perceived that although I have represented this shaft as operating upon one form only a second may be added on the opposite side, and furnished with all the apparatus required for its action, as in that described. This second form will receive its ink from the same rollers as the first will, the two may be rendered by a power considerably less than that which would be required for the single form. What I claim as my invention and for which I ask a patent is the general construction of the letter-pressing machine. Many of the separate parts of which it consists are similar to those hitherto employed in printing and other machines, and these therefore I do not claim as my invention. But I do claim the inking cylinder with the inking rollers according to it in the manner and to the proportions herein set forth. I also claim the manner of passing and operating upon the form by the cranks upon the shafts which pass through the centre

of the inking cylinders. It derives also in the general arrangement of the whole machine from which it receives that peculiar character by which it is distinguished from all others intended for a similar purpose.
